UNITED STATES PATENT OFFICE.

JAMES H. COLLINS, OF HARRISBURG, PENNSYLVANIA.

TOY VEHICLE.

Application filed March 3, 1921. Serial No. 449,483.

To all whom it may concern:

Be it known that I, JAMES H. COLLINS, a citizen of the United States, residing at Harrisburg, in the county of Dauphin and

5 State of Pennsylvania, have invented certain new and useful Improvements in Toy Vehicles, of which the following is a specification.

10 The object of this invention is to provide an article for use by children of tender years, not only as a toy but as a safe means for instructing them how to crawl and walk, and in general to encourage them to make the greatest possible use of their little arms 15 and legs.

Furthermore, it is the object of this invention to provide an article which will so amuse and entertain children as to engage their attention while those caring for 20 them may be engaged in other duties, and particularly with the idea in mind that the present invention will provide them with a toy vehicle which will be applicable to children younger than the age at which they 25 are able to take up the use of so-called kiddie-cars and similar vehicles.

And it is furthermore the object to provide such a device arranged as close as possible to the floor or other surface upon 30 which the child may be playing; to provide a device which can be fixed with respect to a given locality within a room, so that the child playing with the same cannot operate it to dangerous places, such for instance 35 near the head of stairs and the like; to provide a device adapted to be pivotally mounted to operate about a temporarily fixed point, and yet affording quite a substantial range of movement; and to provide 40 a device of this character so constructed in one form that the disc-like platform, adapted to support the child's body, is so closely adjacent to the floor that the child using it will sustain no injury in rolling off of it.

45 With these and other objects in view, the present invention comprises further details of construction and operation hereinafter fully brought out in the following description when read in conjunction with the accompanying drawings, in which Fig. 1 is a top plan view of the preferred embodiment of the invention; Fig. 2 is a side elevation of the same; Fig. 3 is a front end view of the same; Fig. 4 is a plan view of a 50 slightly modified form of the device pivotally mounted to swing around a block, in-

stead of around a point upon a side wall of a room, as shown in Fig. 1; and Fig. 5 is a fragmentary bottom plan view of a still further modification of the invention. 60

Referring to the drawings, a disc 1 of wood or other suitable material and comprising a seat member is provided with a bolster 2 secured to the underside thereof and adjacent to one of the end portions of the said disc, a plurality of suitable wheels 3 being rotatably carried by the said bolster against surfaces 4 of the latter which are preferably angularly disposed with respect to each other for a purpose hereinafter described. 70

The said seat member may be either a plane board 5 as shown in Fig. 4, or as in the preferred form where it comprises an enlarged portion 6 adapted to bear the 75 weight of the child and a forward portion 7 which the child faces and upon which it can let its feet rest, these said portions being connected by a preferably transversely reduced intermediate portion 8. Upon the 80 forward portion may be secured a cut-out member 9 representing the head of any well-known animal of which children are universally fond, the same being provided with hand-gripping members 10, which 85 serve as something by which a child can support himself upon the toy and which will assist him in mounting and demounting the same.

Secured to the lower rear portion of the 90 bolster 2 is the free end of a radius member 11, the same being rigidly fixed with respect to said bolster by means of a brace 12, while the rear portion of the member 1 is spaced above and supported with respect to said 95 radius member by means of a second bolster 13. The radius member itself may continue rearwardly to any desired distance either as a single element or may be cut transversely as shown in the dotted lines 14, in 100 order to provide a section 15 adapted to fold by virtue of a hinge 16 against and parallel with the undersurface of the major portion of said radius member.

Either as a single element, or as a sectional 105 element in extended position, as shown in Figs. 1 and 2, the radius member is provided with either a hook or eye 17 which is adapted to be respectively engaged within a corresponding eye or hook 18 secured to the 110 lower portion 19 of a wall such for instance as the mop-board or subbase. Or, on the

other hand, the eye or hook 18 may as illustrated by Fig. 4 be carried by a block 20, which latter is adapted to be secured removably to any part of the floor of a room or 5 itself secured to the wall.

Said block when secured to the floor being adapted to permit the body to describe a complete circle, the member 18 is secured into a wall as shown in Fig. 1, the wall obviously permitting the toy to describe only a 10 partial circle, which in most cases would approximate 180 degrees.

When a very small child is to use such a toy as is comprised within the scope of this 15 invention, it is generally considered preferable to employ the form shown in Fig. 4, wherein the seat member 5 is secured directly to the radius member 11, and therefore is very close to the ground, so that the child 20 can if desired lie flat upon the seat board and propel the toy by means of its hands and toes extending out over the sides of the seat member 5. It is because of the very nature 25 of the movement of this toy, that is always describing at least an arc of if not a complete circle, that the surfaces 4 are angularly disposed with respect to each other, as are also the wheels visibly attached thereto.

With this construction, the axes of rotation 30 of the wheels converge at the pivotal mounting 17—18, and as a result do not tend so readily to scratch or otherwise mar the floor or covering of the same in an ordinary home.

35 Referring to Fig. 5, a slightly modified form of the device is shown, wherein the radius member 21 is enlarged at 22 in order to provide for an aperture 23, through which is revolvably positioned and adapted to rotate a preferably centrally positioned wheel 24, which wheel obviously adapts the device 40 to support children of considerably greater weight than could ordinarily be carried by the firmness of the device hereinbefore de-

scribed, when no support is provided between the pivotal connection with a fixed member and the wheels at the extreme free end thereof.

However, it is to be understood that this invention also anticipates placing at least the major portion of the weight of the child radially outward beyond the pair of wheels 3, and also there may very likely arise occasions wherein it is desired to reverse the said member and animal's head carried thereby, 55 so that the latter faces towards the wall, this last-named arrangement possessing a particular advantage, in that the weight of the child riding upon the device would be substantially if not exactly above the said 60 wheels.

Having thus described my invention, what I claim and desire to protect by Letters Patent of the United States is:—

1. A readily portable toy, comprising a 65 radius member, a seat member attached to one end of said radius member, a wheel to movably support one end of said first member in spaced relation with respect to a supporting surface, and disengageable means 70 carried by the other end of said radius member to operatively support and readily attach said radius member to any desired object to serve as a center about which said toy can be oscillated.

2. A readily portable toy, comprising a 75 sectional collapsible radius member, a seat member attached to one end of said radius member, bolsters to support said seat in raised spaced relation with respect to said 80 radius member, a supporting wheel connected to one of said bolsters, and pivot means carried by the other end of said radius member to support and readily secure said end in any desired position.

85 In testimony whereof I have affixed my signature.

JAMES H. COLLINS.
